Primary Examiner — Barbara Fox*Assistant Examiner* — Messina L Smith(74) *Attorney, Agent, or Firm* — Antonio Papageorgiou,
 Esq.; Meister Seelig & Fein LLP(57) **CLAIM**

The ornamental design for a grill pan, as shown and described.

DESCRIPTION

FIG. 1 is a perspective view of the front, left side, and bottom of a grill pan, showing my new design.

FIG. 2 is another perspective view of the front, left side, and bottom thereof;

FIG. 3 is another perspective view of the front and bottom thereof;

FIG. 4 is a front view thereof;

FIG. 5 is a perspective view of the rear, right side, and top thereof; and,

FIG. 6 is another perspective view of the rear, right side, and top thereof.

The broken lines in the drawings depict portions of the grill pan that form no part of the claimed design.

1 Claim, 6 Drawing Sheets(56)
